The ornamental design for a toy building element, as shown and described.

DESCRIPTION

It is intended that the toy building element of the present invention be used in a set of toy building elements that are capable of being interconnected in a releasable engagement. FIG. 1 is a top perspective view of the toy building element. FIG. 2 is a top view of the toy building element shown in FIG. 1.

FIG. 3 is a front view of the toy building element shown in FIG. 1.

FIG. 4 is a back view of the toy building element shown in FIG. 1.

FIG. 5 is a left side view of the toy building element shown in FIG. 1; and,

FIG. 6 is a right side view of the toy building element shown in FIG. 1.

The bottom view of the toy building element shown in FIG. 1 does not form part of the claimed design.
